UNITED STATES PATENT OFFICE.

EDWARD S. SMITH, OF WATERBURY, CONNECTICUT.

CLASP OR BUCKLE.

SPECIFICATION forming part of Letters Patent No. 338,792, dated March 30, 1886.

Application filed September 15, 1885. Serial No. 177,135. (No model.)

To all whom it may concern:

Be it known that I, EDWARD S. SMITH, a citizen of the United States, residing at Waterbury, county of New Haven, and State of Connecticut, have invented certain new and useful Improvements in Spring Clasps or Buckles, fully described and represented in the following specification, and the accompanying drawings, forming a part of the same.

10 The object of this invention is the production of a spring clasp or buckle simple in structure and composed of parts formed, connected, and related so that when the buckle is closed it may be locked, while the opening 15 of its holding-lever shall be opposed by a spring of considerable power, and which spring shall, during the opening and closing movement of the holding-lever, apply such a frictional resistance to its movement as to 20 cause the same to be evenly made or enable it to stand in any position to which it may be moved, at the same time admitting the holding-lever to be extended forward in an appropriate position to receive the locking 25 member with which it is to be engaged. Another object attained by the construction is the production of a clasp or buckle, the total thickness of which is comparatively small, and thus does not tend to unduly project beyond 30 the surface to which it is attached.

The invention consists in the novel structure and combination of parts to be hereinafter specifically described and claimed.

In the drawings illustrating this invention, 35 Figure 1 is a plan view of the clasp or buckle open. Fig. 2 is a similar view with the holding-lever closed, but having its long arm removed. Fig. 3 is a side elevation of the clasp or buckle closed and its holding-lever engaged with a fastening or looped plate; and Figs. 6, 7, and 8 are plan views respectively illustrating the blanks composing the top plate, the bottom plate, and the holding-lever. Fig. 9 is a sectional view showing a modification of the plate B and its bearing 45 5.

The body of the buckle is composed of two plates, A B, one or both made of spring metal and united together in any suitable way, as by rivets C. The bottom-plate, A, has side 50 arms, 2 3, united by a narrow bar, 4, that constitutes a pintle for the holding-lever E to swing on. The top plate, B, carries at its

front end a bearer, 5, that co-operates with the knuckle of the lever E, and this plate is perforated, as at D, so as to provide a means 55 for fastening the clasp or buckle in place. The holding-lever E is formed from a blank (see Fig. 8) of a width suiting it to turn between the arms 2 3. Its inner end is slotted centrally, so that when this end is curved or bent 60 to form the knuckle 8 the inner portion of said knuckle will be provided with a recess, 6, in proper relation for coaction with the bearer 5 of the top plate, B. Preferably the bearer 5 and recess 6 are arranged centrally, 65 and have somewhat narrow proportions, but there may be two of them, or their longitudinal dimensions may be increased. The body of the lever E is bent so as to form a hold-back, 9, and a rearwardly-extending arm, as 70 is common. This construction of the parts is such that when the holding-lever E is mounted to turn upon the pintle 4, and is closed, as in Figs. 2, 3, 5, the bearer 5 of the plate B will lie in the recess 6 of the plate A, and reaching 75 through the knuckle 8 rest upon the pintle 4 of the lower plate, thus leaving the holding-lever loosely hung on the pintle and prevented from unduly moving, being confined against an opening movement by the abutment 10 of 80 the knuckle engaging the under side of the bearer 5, (see Fig. 5,) in which relation the parts of the clasp or buckle are in position to secure the attaching-plate T, as in Fig. 3.

In the operation of opening the clasp or 85 buckle to release the attaching-plate T the holding-lever is raised and thrown forward. In this movement the abutment 10 immediately engages the under side of the bearer 5, and thus forces the plates A B apart, their 90 spring-power being applied to the knuckle of the holding-lever as a brake opposing its free movement. This continues so long as the lever is being moved from the position of Fig. 5 to that of Fig. 4, and vice versa, and when the 95 rearward position is attained, as in Fig. 5, the abutment 10 and bearer 5 form a lock securing the closed position of the clasp or buckle.

Of course the pintle 4 may be provided in connection with the plate B and the bearer 5 100 be upon the plate A.

Instead of the bearer 5 being raised above the plane of the plate B or curved, it may, as in Fig. 9, lie in the same plane and be flat.

What is claimed is—

1. In spring clasps or buckles, the combination, with a holding-lever the knuckle of which is provided with a recess, as 6, of a bearer carried by the body of the clasp or buckle, adapted to engage with said recess, substantially as described.
2. A body-plate for a spring clasp or buckle, one member of which is provided with a pin-tle, as 4, and the other with a bearer, as 5, adapted to co-operate with a recessed lever, substantially as described.
3. A spring clasp or buckle, consisting of a

body-plate comprised in two members, one of which is provided with a pintle, 4, and the other with a bearer, 5, and a holding-lever hung to swing on the pintle 4, and having its knuckle provided with a recess, as 6, substantially as described.

In testimony whereof I have hereunto set my hand in the presence of two subscribing witnesses.

EDWARD S. SMITH.
